UNITED STATES PATENT OFFICE.

FRANKLIN FREY, OF QUINCY, ILLINOIS, ASSIGNOR OF ONE-HALF TO
CALDWELL LADD, OF SAME PLACE.

HAY-PRESS.

SPECIFICATION forming part of Letters Patent No. 269,659, dated December 26, 1882.

Application filed November 15, 1882. (Model.)

To all whom it may concern:

Be it known that I, FRANKLIN FREY, a citizen of the United States, residing at Quincy, in the county of Adams and State of Illinois, have invented certain new and useful Improvements in Hay-Presses; and I do declare the following to be a full, clear, and exact description of the invention, such as will enable others skilled in the art to which it appertains to make and use the same, reference being had to the accompanying drawings, and to the letters and figures of reference marked thereon, which form a part of this specification.

The object of my invention is to provide a hay-press having superior construction in the bale-chamber, sweep, and lever mechanism.

The nature of my invention will appear in the following description of the above parts and their necessary connections.

Figure 1 is a side view, showing the position of the parts when the follower is forced fully in to press the hay. Fig. 2 is a plan view, showing the position of the parts under like circumstances. Fig. 3 is a plan view, partly in broken section, showing the position of the sweep and lever mechanism when the sweep has been carried forward to retract the follower. Fig. 4 is a detail view of the sweep and yoke. Fig. 5 is a detail view showing the manner of locking the sweep when drawn back.

Like letters refer to like parts in the drawings.

The press is mounted on wheels, so that it can be moved from place to place. The main frame-work consists of two lower beams, A B, resting on the trucks, and the upper beams, C D, separated from the lower by the standard E, the outer end, F, of the bale-chamber, and the intermediate supports, the whole being suitably bolted together at intervals to give necessary strength. (See Figs. 1 and 3.)

The bale-chamber is at the forward end of the press, the floor and end being solid and immovable. The end F is strengthened in front by horizontal bars of metal a a, which are prevented from bulging out by the bolts b b passing from the lower beams to the upper. Furthermore, the middle bar is fastened by a staple driven into the end of the bale-chamber, and the upper and lower bars are fastened to the cross-ties between the beams.

The sides of the chamber are formed by doors G G. These doors are hinged upon bolts b b, and provided on the outside with inclined bridges b' b', carrying a latch, t. On the inside of the doors are placed metallic hooks h h, for retaining the hay in the bale-chamber and preventing it from slipping back while the follower is at work. When the press is in operation the doors are closed by slipping the bars H H, hinged to the beams, upon the inclined bridges, and fastening them there by the latches t; but when a sufficient amount of hay has been pressed said doors are easily opened for putting on the ties and removing the bale.

At the top of the bale-chamber is placed a pressure-relief door, I. This door is fastened in the same way as the side doors, but is shorter, has a cross-bar, e, to prevent it from falling inward, and is hinged to the bolt d, between the upper beams, at a distance farther back than the side doors are, in order to withstand the upward pressure the better.

Behind the door I is arranged the hopper J for feeding the hay to the bale-chamber when the follower is retracted; but as said hopper is of an ordinary construction it will not be described.

At the side of the press, as shown, and extending nearly to the rear, is constructed a strong frame. Extending out from this are two triangular metallic supports, e e, forming a journal for the vertical metallic axle K. Upon this axle the yoke L and sweep M swing in nearly a semicircular arc. The former is placed about the latter near the end, and has its end largely shod with metal. From this facing projects a conical stud, f, and there is also a recess, g. (All shown in Fig. 4.) The stud extends through the end of the yoke to form a hook, h', to which the main-lever chain is attached. The sweep M is provided at its inner end with a metal facing, a circular disk, i, and a groove j for supporting and guiding the chain; also with a sliding spring-bolt, k, engaging at one end with the recess g of the yoke and curving up at the other end to engage with a hinged lever, l, on the top of the sweep; also with a hinged hook, m, engaging with a curved lever, n, attached to the side frame. (See Fig. 3.) The lever n has a projection, o, at one end to fit into the hook m; but the other end is

curved inward to properly engage with the knuckle-joint to quickly throw said joint out of the dead-center and retract the follower.

The standard E has firmly fixed thereto a 5 guide, *p*, for the sweep, and an arm, *r*, for actuating the lever *l* at the top of the sweep. The shape and arrangement of the guide and arm are shown in Figs. 2 and 5. The guide may support the curved lever also.

10 From the end of the hook *h'* in the yoke the chain *N* connects the sweep with the knuckle-lever *O*. This lever, which may also be called the "operating-lever," is composed of two arms, *s s'*, one pivoted to the standard E, the other 15 to the rear extension of the follower. They are joined at the center through their overlapping reduced ends of metal by a pin. Thus the arms are easily bent and straightened.

15 The inner portion of the follower is made 20 solid, and has its face provided with grooves to correspond to those opposite in the end of the bale-chamber, so that ties may be easily applied. The outer end of the follower is made hollow to give ready attachment to the inner 25 arm of the knuckle-lever and to give play to the same. This construction also guides and steadies the follower.

30 The operation of the press is, briefly, as follows: The sweep is carried forward by the team until the sliding bolt of the sweep engages with the yoke carrying the lever-chain. The sweep is then carried back until the hinged hook locks with the curved lever, and the hinged lever sliding upon the inclined face of the fixed arm releases the spring-bolt. By this time the knuckle-lever is straightened out and the follower driven home. When 35 the sweep starts forward the yoke and lever-chain swing free, and the sweep has to act on the curved lever only. Almost at the same time the hinged hook draws the curved lever inward, throwing the knuckle-lever at once out of the dead-center and quickly retracting the follower. When this has been done the hinged 40 hook passes clear of the outer end of said curved lever and the sweep goes forward free of all strain until the spring-bolt again engages with the yoke to repeat the operation.

45 The advantages of my press will appear from the above. By passing the chain from the yoke about the side and end of the sweep great and steady power is given the knuckle-lever, while the disk and groove give support and guidance to the chain. After the yoke 50 engages the sweep the power is not applied to the chain until the sweep has passed nearly to a right angle with the side of the press, giving a quick motion and great force. However, this may be varied by lengthening or shortening 55 the chain. By the automatic shifting and unshipping of the yoke the men are saved labor and speed is gained; also, the sweep is released from strain on the forward movement. The knuckle-lever being quickly bent by the 60 curved lever, the follower is retracted at once, as it were, and the men are given nearly dou-

ble the ordinary time to feed hay. Hence they can feed more hay at one charge than formerly, and the bale will be formed more rapidly.

Having fully described my invention, what I 70 claim is—

1. The sweep having a metallic supporting-disk and guiding-groove at the end thereof, as shown, combined with the operating-lever and follower, substantially as set forth. 75

2. The combination of the sweep and yoke, with the operating-lever and follower, as set forth.

3. The combination of the yoke with the sweep provided with a spring-bolt, as set forth. 80

4. The combination of the spring-bolt with the yoke having a recess in the end thereof for receiving said bolt, as set forth.

5. The combination of the yoke with the sweep having spring-bolt and hinged lever 85 and the fixed arm upon the end of the standard, substantially as set forth.

6. The combination of the sweep having hinged hook with the curved lever engaging the operating-lever, as set forth. 90

7. The combination of the operating-lever having a curved projection on one of its arms for engaging with the curved lever, with said curved lever, as set forth.

8. The combination of the operating-lever 95 with the curved lever and the sweep, as set forth.

9. The combination of the operating-lever, composed of two arms, as shown, with the follower and sweep, as set forth. 100

10. The combination of the chain attached to the yoke, as shown, and passing around the side and end of the sweep, with the operating-lever, whereby the power is applied quickly and strongly to the center of said lever, as set 105 forth.

11. The combination of the frame at the side of the press, supporting the vertical axle and curved lever, with said axle, lever, and the sweep, as set forth. 110

12. The combination of the guide on the standard with the sweep and curved lever, as set forth.

13. In a hay-press, the side doors provided with metallic hay-retaining hooks, as set forth. 115

14. In combination with the bale-chamber, the side doors having an inclined bridge and latch and the fastening-bars attached to the sides of the press, as set forth.

15. In combination with the bale-chamber, 120 the top pressure-relief door, as set forth.

16. In combination with the bale-chamber, the top pressure-relief door, hinged as shown, and provided with an inclined bridge and latch, and the fastening-bar attached to the top of 125 the press, as set forth.

In testimony whereof I affix my signature in presence of two witnesses.

FRANKLIN FREY.
